ABSTRACT

A frame includes a scraper which provides support for pivoted shoe brushes that rest upon and conceal the scraper except when pivoted aside to expose the scraper for use.

SHOE BRUSH AND SCRAPER

BACKGROUND OF INVENTION

In the usual shoe brush the brush or brushes are fixed. Any desired scraper is mounted in an exposed position where it tends to be cumbersome and to tend to trip unwary users.

SUMMARY OF INVENTION

An extremely compact organization results because the scraper is a part of the frame which supports the pivoted shoe brushes for use and is exposed when the brushes are pivoted aside.

BRIEF DESCRIPTION OF DRAWINGS

FIG. 1 is an end elevation of a device embodying the invention.

FIG. 2 is a plan view of the device shown in FIG. 1 with one of the scraper brushes pivoted aside to expose the underlying scraper.

FIG. 3 is a view taken in section on the line 3—3 of FIG. 1.

DETAILED DESCRIPTION

As a support for the brushes, frame 6 comprises two generally triangular legs 8 and 10 each having a foot portion 12 which may desirably be encased in a rubber tube 14. These legs support elements such as the angles 16 connected to each other by a cross member 28 and having end closures 18 through which pass pintle bolts 20. Upon these bolts are pivoted the respective brushes 22, each of which has a wooden back at 24 from which the bristles 26 project as best shown in FIG. 1. The pintle bolts 20 are above the level of the angles 16 so that the individual brushes may readily be swung upwardly from the position of FIG. 1 to the position in which the lefthand brush 22' is illustrated in FIG. 2.

A cross member connecting the angles to complete the frame includes a strong blade 28 constituting a scraper extending transversely between the legs 8. When the brushes are

pivoted aside this blade is exposed. When the brushes are pivoted to the position of FIG. 1, the brush backs 24 rest on the blade 28, which provides support to hold them in operative position for use.

5 The scraper blade is effective upon a shoe drawn between the brushes when the brushes are in the shoe-brushing position of FIG. 1. However, it is out of sight and normally will be used only when exposed as shown at the left in FIG. 2. Because the cross member 28 is disposed midway between the legs, the 10 frame is very stable when either the scraper or the brushes are in use. In addition, the scraper is not exposed in a position in which people might trip over it. The whole assembly is extremely compact.

What is claimed is:

- 15 1. A shoe brush organization comprising supports spaced endwise, each support comprising a transverse foot member and upright leg members, brackets of angle-shaped cross section extending endwise between the supports and respectively having their ends attached to corresponding legs of said supports for connection of said supports to each other, brushes 20 with backs extending along the respective brackets and having ends in pivotal connection with opposite supports and having bristles which in corresponding brush portions may extend toward each other, and a scraper attached at its ends to said brackets and thereby mounted on said supports and over which said brush bristles are normally superimposed, the brushes being mounted for relative movement on their pivotal connections to retract their bristles to scraper-exposing position.
- 25 2. A shoe brush organization according to claim 1, in which the brushes have intermediate portions of their backs normally resting upon the scraper to receive support therefrom when the brushes are in a position for use.
- 30 3. A shoe brush organization according to claim 2 in which said brackets have terminal ears through which extend pintles providing the said pivotal connection of the brush ends with said brackets, the scraper comprising a blade connected to said angles intermediate their ends.
